GEORGE R. FARIA

83rd Harry C. Schroeder
Attorney

UNITED STATES PATENT OFFICE.

GEORGE R. FARIA, OF OAKLAND, CALIFORNIA, ASSIGNOR OF ONE-HALF TO HARRY ANDREWS, OF OAKLAND, CALIFORNIA.

DRUM PEDAL.

Application filed February 11, 1922. Serial No. 535,888.

To all whom it may concern:

Be it known that I, GEORGE R. FARIA, a citizen of the United States, residing at Oakland, in the county of Alameda and State of California, have invented certain new and useful Improvements in Drum Pedals, of which the following is a specification.

My invention is a drum hammer pedal which may be detachably secured to the rim of the drum and may be folded flat when not in use.

Referring to the annexed drawing in which my invention is illustrated and which forms a part of this specification:

Figure 1 is a side elevation of my invention in position for use.

Figure 2 is a horizontal sectional view of my invention.

Figure 3 is a partial longitudinal section of my invention on an enlarged scale taken on line 3—3 of Figure 2.

Figure 4 is a longitudinal section of my invention taken on line 3—3 of Figure 2 with the hammer folded flat.

In the drawing 1 indicates a pedal frame comprising side walls 2 and connecting members 3, 4 and 5, which connect said walls at their lower edges, the members 3 and 5 connecting said walls at their front and rear ends and the member 4 connecting said walls intermediate their ends, nearer their front ends. Slots 6 are cut horizontally in the forward ends of the frame walls 2 to receive the rim of the drum and inturned lugs 7 are formed on said walls at the upper edges of said slots through which lugs extend vertical set screws 8 for engaging the drum rim to secure the frame to the drum. Vertical lugs 9 extend upwardly from the upper edges of the walls 2 just back of the lugs 7. The forward ends of the walls 2 are provided with slots 10 which extend vertically into the lugs 9 and are curved rearwardly and slightly upwardly from their lower ends as indicated at 11. A pin 12 extends transversely of the forward end of the frame through the slots 10, on which pin are journaled two cams 13 and 14. Hammers 15 and 16 are secured at the ends of their handles to the cams 13 and 14 respectively. To either hammer is suitably secured a cymbal striking wire 16a.

Flat springs 20 and 21 are secured at their rear ends to the connecting frame member 4

and bear at their forward ends against the underside of the cams 13 and 14 respectively to hold said cams in operative position with the ends of the pin 12 in the upper rearwardly curved ends 11 of slots 10 and to return the hammers to their initial operative position when they are actuated. Lugs 22 and 23 project rearwardly from the cams 13 and 14. Pedals 25 and 26 are pivoted on the frame 1 between the walls 2 on a pivot pin 27 secured in said walls. Metal bushings 28 are secured in said pedals through which the pin 27 extends. Metal bushings 29 are secured in the cams 13 and 14 through which extends the pin 12. On the forward ends of the pedals 25 and 26 are lugs 30 and 31 which rest respectively under the cam lugs 22 and 23 when the hammers 15 and 16 are in operative position. Rubber strips 32 and 33 are secured to the upper sides of the pedals 25 and 26 respectively and the forward ends of said strips cover the cam lugs 22 and 23 respectively when the hammers are in operative position. Legs 35 depend from the front cross member 3 and legs 36 and 37 depend from the rear cross member 5 which legs rest on the floor and support the frame 1. Set screws 38 and 39 are seated in the rear connecting member 5 and respectively in the legs 36 and 37. Lock nuts 40 and 41 screw on the set screws 38 and 39 against the cross member 5. The set screws 38 and 39 are directly under the rear ends of the pedals 25 and 26 respectively and adjustably limit the downward movement of said pedals and thereby regulate the throw and force of the hammers 15 and 16.

The pin 12 may be shifted from the curved ends 11 of the slots 10 to the upper end of the vertical portion of said slots to fold the hammers 15 and 16 down upon the pedals 25 and 26 respectively as shown in Figure 5 in which position the device may be conveniently carried about.

Having described my invention, I claim:

1. In combination, a frame provided with slots in its forward end, said slots extending vertically and rearwardly curved upwardly at their lower ends, a pin extending into said slots, a weighted cam journaled on said pin, a lug extending rearwardly from said cam, a pedal mounted on said frame, a lug on the forward end of said pedal adapted to rest under the lug of said cam when the cam is in

position with said pin in the curved rear ends of said slots, and a hammer on said cam.

2. In a drum hammer operating mechanism, a supporting frame, vertical lugs attached to the sides of the frame, said lugs provided with J shaped slots, a cam, oppositely extending pins carried by the cam and inserted in the slots, drum beater means operated by the cam and means adapted to operate the cam.

3. In a drum hammer operating mechanism, a frame, lugs attached to opposite sides of said frame and provided with slots, said slots extending vertically for a portion of their lengths and rearwardly curved upwardly at their lower ends, a drum hammer structure carrying pivot pins in said slots, the rearwardly curved portions receiving the pivot pins when the hammer is

in operative position and the vertically extending portion holding the pin and hammer in inoperative position.

4. In a drum hammer operating mechanism, a frame, vertical lugs connected to the sides of said frame, a curved slot in each of said lugs, a cam, pins carried by said cam extending into said slots, means for operating said cam and a hammer operated thereby.

5. In a drum hammer operating mechanism, a frame, vertical lugs connected to the sides of said frame, a curved slot in each of said lugs, a cam, pins carried by said cam extending into said slots, means for operating said cam and a hammer operated thereby, and means for holding said pins in one or the other ends of said slots.

In testimony whereof I affix my signature.

GEORGE R. FARIA.
